UNITED STATES PATENT OFFICE.

HYMAN SHLAMOWITZ, OF BROOKLYN, NEW YORK.

DESIGN FOR A BRACKET FOR THE HEAD-RING OF AN ELECTRIC-LIGHT FIXTURE.

59,937.

Specification for Design.

Patented Dec. 6, 1921.

Application filed April 22, 1921. Serial No. 463,640. Term of patent 14 years.

To all whom it may concern:

Be it known that I, HYMAN SHLAMOWITZ, a citizen of the United States, and a resident of the city of New York, borough of Brooklyn, in the county of Kings and State of New York, have invented a new, original, and ornamental Design for a Bracket for the Head-Ring of an Electric-Light Fixture, of which the following is a specification, reference being had to the accompanying drawing, forming a part thereof.

The invention relates to head rings for

electric light fixtures, such, for instance, as shown and described in the Design Patent of the United States, No. 55,400, granted to me June 1, 1920.

The figure is a perspective view of a bracket for the head ring of an electric light fixture showing my new design.

I claim:

The ornamental design for a bracket for the head ring of an electric light fixture, as shown.

HYMAN SHLAMOWITZ.
